UNITED STATES PATENT OFFICE

GERHARD BRAF, OF NEW YORK, N. Y.

HEMMER.

1,371,600.

Specification of Letters Patent. Patented Mar. 15, 1921.

Application filed March 23, 1918, Serial No. 224,207. Renewed February 3, 1921. Serial No. 442,325.

To all whom it may concern:

Be it known that I, GERHARD BRAF, a citizen of the United States, and resident of the borough of Manhattan, in the city and State of New York, have invented a new and useful Improvement in Hemmers, of which the following is a specification.

The object of my invention is to provide a hemmer for sewing machines which will have novel features of construction, form and arrangement of parts whereby an elastic core may be inserted at the time of forming the hem and the hem moved laterally at predetermined intervals to cause the 10 stitches of the hem to pass through the elastic core to secure the core to the hem; means being provided for adjustably exerting tension on the elastic core as it passes through the hemmer so that the hem will be contracted lengthwise and thereby puckered when the stretched elastic core is released and allowed to return to its normal condition.

This renders the hem particularly well 25 adapted for any purpose where an elastic hem might be used.

A practical embodiment of my invention is represented in the accompanying drawings, in which—

30 Figure 1 represents in top plan the hemmer and so much of a sewing machine as will give a clear idea of the application of the invention,

Fig. 2 represents the same in front elevation, and

35 Fig. 3 represents a portion of a completed hem with its elastic core.

The sewing machine table is designated by 1, the presser foot by 2 and the needle by 3.

40 The fixed member of the hemmer comprises a base 4 having a rear extension plate 5 provided with an arm 6 having an upturned end 7. This extension plate 5 is secured to the base 4 by pairs of screws 8. A slotted bar 9 is pivoted to the extension plate 5 by a screw 10. Spring washers 11 are provided for frictionally retaining the bar 9 in its different adjusted positions with 45 respect to the base 4.

Screws 12 pass through elongated slot 13 in the bar 9 to adjustably secure the fixed member to the sewing machine.

50 The base 4 has a groove 14 within which the shank 15 of the movable member of the hemmer is fitted to slide to adjust the posi-

tion of the movable member laterally with respect to the needle 3.

A hand lever is pivoted at 16 to the lug 17 of the base 4 and its inner arm 18 is engaged with a pin 19 uprising from the shank 15 of the movable member. The outer arm 20 of this lever is provided with a suitable handle 21.

A retracting spring 22 extends between 65 the upturned end 7 of the arm 6 and a lug 23 on the inner arm 18 of the hand lever serving to hold both the movable member and the hand lever at the limits of their rearward movement. A bridge 24 is secured 70 across the outer end of the groove 14, which bridge serves, together with the extension plate 5, to retain the shank 15 of the movable member in the groove 14.

A keeper 25 has elongated slots 26 through 75 which the screws 8 pass and by means of which the keeper is adjusted to limit the outward swinging movement of the hand lever.

The outer end of the shank 15 of the movable member is provided with a sheet metal 80 plate bent and shaped to form top and bottom guides 27 and 28 and a funnel 29 having an inner passage 30 for receiving the elastic core 31 and an outer passage 32 for receiving the material 33 and turning it 85 over to form the hem around the elastic core.

Means are provided for placing the elastic core under tension to stretch it as it passes through the hemmer, which means are shown, in the present instance, as comprising a movable pressure bar 34 hinged at 35 and provided with an end 36 arranged to cramp the elastic core between it and the wall of the inner passage 30.

An adjusting screw 37 turning through 95 a lug 38 on the top guide 27, has its inner end engaged with the pressure bar 34 for moving the pressure bar to secure the desired amount of pressure on the elastic core.

In operation, the hemmer is adjusted 100 with proper relationship to the needle 3 of the sewing machine and the material, together with the elastic core, is fed into the funnel 29. As the material and the core pass through the funnel, the core is 105 stretched and the hem formed around the same and stitched. When it is desired to attach the elastic core to the hem, the hand lever is moved to swing the movable member of the hemmer laterally thus bringing 110 the stitches of the hem through the core. The desired amount of pressure on the elas-

tic core to put it under the proper tension, can be adjusted.

It is evident that changes may be resorted to in the form, construction and arrangement of the several parts without departing from the spirit and scope of my invention; hence I do not intend to limit myself strictly to the structure herein shown and described, but

10 1. What I claim is:—

15 1. A hemmer for sewing machines, including a member shaped to receive an elastic core and to receive and turn material to form a hem around the elastic core, means carried by the member for placing the elastic core under tension as it passes through the hemmer and means for moving the member laterally to bring the stitches of the hem through the core at predetermined 20 points in the hem without releasing the tension on the elastic core.

25 2. A hemmer for sewing machines, including a fixed member for attachment to the sewing machine, a movable member shaped to receive an elastic core and to receive and turn material to form a hem around the elastic core, means carried by the movable member for placing the elastic core under tension as it passes through the hemmer, and means carried by the fixed member 30 for moving said movable member to bring the stitches of the hem through the core at predetermined points in the hem without releasing the tension on the elastic core.

35 3. A hemmer for sewing machines, including a member provided with a funnel

having an inner passage for receiving an elastic core and an outer passage for receiving and turning material to form a hem around the elastic core, and pressure means 40 carried by the member coacting with the wall of the inner passage to place the elastic core under tension as it passes through the hemmer.

4. A hemmer for sewing machines, including a sheet metal blank bent and shaped to form top and bottom guides for the material to be hemmed and to form a funnel having an inner passage for receiving an elastic core and an outer passage for receiving and turning material to form the hem around the elastic core, and a pressure device carried by the top guide for placing the elastic core under tension as it passes through the hemmer.

5. A hemmer for sewing machines, including a fixed member for attachment to the sewing machine and a movable member having a lateral sliding movement in the fixed member and provided with a funnel 60 having an inner passage for receiving an elastic core and an outer passage for receiving and turning material to form a hem around the elastic core and means carried by the fixed member for moving the movable member laterally to bring the stitches of the hem through the core at predetermined points in the hem.

In testimony that I claim the foregoing as my invention, I have signed my name 70 this 22nd day of March, 1918.

GERHARD BRAF.
